(57) **CLAIM**

The ornamental design for a lighting fixture, as shown and described.

DESCRIPTION

FIG. 1 is a front side view of an embodiment of a lighting fixture according to the new design;

FIG. 2 is a bottom view of the lighting fixture of FIG. 1; FIG. 3 is a front, top perspective view of the lighting fixture of FIG. 1;

FIG. 4 is a front, bottom perspective view of the lighting fixture of FIG. 1;

FIG. 5 is a back side, exploded view of the lighting fixture of FIG. 1;

FIG. 6 is a back, top, perspective, exploded view of the lighting fixture of FIG. 1;

FIG. 7 is a back, bottom perspective, exploded view of the lighting fixture of FIG. 1;

FIG. 8 is a front side view of an embodiment of a lighting fixture according to the new design;

FIG. 9 is a bottom view of the lighting fixture of FIG. 8;

FIG. 10 is a front, top, perspective view of the lighting fixture of FIG. 8;

FIG. 11 is a front, bottom, perspective view of the lighting fixture of FIG. 8;

FIG. 12 is a back side view of the lighting fixture of FIG. 8;

FIG. 13 is a back, top, perspective view of the lighting fixture of FIG. 8;

FIG. 14 is a back, bottom, perspective view of the lighting fixture of FIG. 8;

FIG. 15 is a front side view of an embodiment of a lighting fixture according to the new design;

FIG. 16 is a bottom view of the lighting fixture of FIG. 15;

FIG. 17 is a front, top, perspective view of the lighting fixture of FIG. 15;

FIG. 18 is a front, bottom, perspective view of the lighting fixture of FIG. 15;

FIG. 19 is a back side, exploded view of the lighting fixture of FIG. 15;

FIG. 20 is a back, top, perspective, exploded view of the lighting fixture of FIG. 15; and,

FIG. 21 is a back, bottom, perspective, exploded view of the lighting fixture of FIG. 15.

The broken lines in the drawings are directed to unclaimed portions of the lighting fixtures. Accordingly, the broken lines form no part of the claimed design.

1 Claim, 21 Drawing Sheets
